UNITED STATES PATENT OFFICE.

CHARLES B. ULRICH, OF HOUGHTON, MICHIGAN, ASSIGNOR TO ART METAL CONSTRUCTION COMPANY, OF JAMESTOWN, NEW YORK, A CORPORATION OF MASSACHUSETTS.

METALLIC SHELVING.

1,261,654.

Specification of Letters Patent.

Patented Apr. 2, 1918.

Application filed April 6, 1915. Serial No. 19,591.

To all whom it may concern:

Be it known that I, CHARLES B. ULRICH, a citizen of the United States, residing at Houghton, in the county of Houghton and State of Michigan, have invented certain new and useful Improvements in Metallic Shelving, of which the following is a specification.

This invention relates to shelving and 10 more particularly to metallic shelving.

While the present invention is of general application, it is particularly designed for the support and storage of boxes, for instance, shoe boxes to the retail trade, and it 15 is an important object of the present invention to obtain the maximum storage capacity, and at the same time to provide a strong, rigid and durable structure which may be conveniently set up and maintained 20 in a tight and rigid condition.

The shelving may be put up in sections of any desired length and height, and may be conveniently added to, as may be required from time to time without dismantling or 25 otherwise interfering with the section or sections already set up.

With these and other objects in view, the present invention consists in the combination and arrangement of parts, as will 30 be hereinafter more fully described, shown in the drawings, and particularly set forth in the appended claims, it being understood that changes in the form, proportion, size and minor details may be made, within the 35 scope of the claims, without departing from the spirit or sacrificing any of the advantages of the invention.

In the drawings,

Figure 1 is a fragmentary perspective 40 view of shelving embodying features of the present invention.

Fig. 2 is an enlarged detail cross-sectional view on the line 2--2 of Fig. 1.

Fig. 3 is a fragmentary view of an upright 45 showing a pair of openings therein for the reception of shelf members.

Fig. 4 is a detail sectional view on the line 4--4 of Fig. 1, showing one form of means 50 for anchoring a shelf to an end upright.

Fig. 5 is a detail perspective view of one 55 of the anchor devices employed in Fig. 4.

Fig. 6 is a detail plan section taken

through an upright in the plane of the upper face of a shelf, as shown in Fig. 1 of the drawings.

Fig. 7 is an end view illustrating an anchor device of the type shown in Fig. 5.

Fig. 8 is an end view illustrating another manner of anchoring a shelf.

Fig. 9 is a detail sectional view on the line 60 9--9 of Fig. 8.

Fig. 10 is a view similar to Fig. 2 and showing a modified form of shelf.

Fig. 11 is an elevation of a portion of an upright having an opening to accommodate 65 the form of shelf shown in Fig. 10.

Fig. 12 is a view similar to Fig. 6, and showing the form of shelf employed in Fig. 10.

Fig. 13 is a detail fragmentary perspective view illustrating the manner of keying 70 a shelf to an upright.

Fig. 14 is an end view illustrating another form of anchoring means for the end of a 75 shelf.

Fig. 15 is an end view showing another form of anchoring means.

Fig. 16 is a view similar to Fig. 4, showing 80 a form of anchor device as employed with the form of shelf shown in Fig. 10.

Fig. 17 is a detail horizontal sectional view taken through the end upright of adjacent shelving sections.

Fig. 18 is a detail view of an end of a shelf member as employed in Fig. 14 of the drawings.

Fig. 19 is a detail sectional view of another embodiment of shelf.

Like characters of reference designate corresponding parts in each of the several figures of the drawings.

As best shown in Fig. 1 of the drawings, it will be seen that the present shelving includes, generally, a base A, uprights B, and shelves C. The base may be of any common or preferred construction, as it forms no part of the present invention, which invention involves the shelf construction and the manner of connecting the shelf with the uprights so as to tie together the uprights and shelves in a simple and economical manner and to provide a strong and rigid structure.

The form of shelf employed in Fig. 1, is shown in detail in Figs. 2, 6 and 13. As

best illustrated in Fig. 2, it will be seen that this form of shelf includes front and rear shelf members D and E, and a third member in the form of a cover plate C. The front and rear shelf members are duplicates in construction and mounting, and therefore a description of one of them will be sufficient. Each shelf member is of a length to extend across several uprights and is a single metallic strip or plate, having a longitudinal rib 1 struck downwardly therefrom throughout its entire length and disposed substantially midway between its front and rear edges. Besides stiffening the shelf member, this rib has another function, as will be hereinafter explained. The rear edge or side 2 of the rib is disposed at substantially right angles to the plane of the shelf and constitutes a depending abrupt shoulder or abutment, while the front edge portion 3 of the rib inclines upwardly and forwardly and merges into the body of the plate at an obtuse angle, so as to form a beveled front face or edge. As clearly shown in Fig. 3 of the drawings, each upright B is provided with front and rear slots or openings F and G. Each of these slots or openings is disposed in a substantially horizontal position, is of a shape corresponding to the cross-sectional shape of one of the shelf members, and has a length slightly exceeding the width of the shelf members. As the two front and rear shelf members are intended to support the same cover plate, it is of course apparent that the slots or openings are in the same horizontal plane.

In assembling the shelving, the uprights are placed in position and the shelf members are driven endwise through the aligned slots or openings in the uprights, and then keys, such as shown at 4, in Figs. 6, 12 and 13 are driven into the respective slots or openings in the uprights, so as to bear against the shoulders 2 of the shelf members and the shoulders 5 of the slots, whereby the shelf members will be driven edgewise toward the front of the structure. By reference to Fig. 6 of the drawings, it will be seen that the front edge of each shelf member is provided with a slit or notch 6 which receives the front edge of the opening in the upright, whereby the shelf member is interlocked with each upright and held against endwise movement. The shelf member may be readily loosened preparatory to removing it from the structure merely by driving out the keys. Inasmuch as the ribs 1 of the shelf members are on the under sides of the members, the keys are hidden from view. The beveled or inclined front edge portions 3 of the ribs facilitate the introduction of boxes, for the reason that such inclined portions do not offer abrupt obstructions to the upper edges of the boxes when being thrust into a compartment defined by adjacent shelves and

adjacent uprights. If the rear end portion of the cover of a box has been elevated by the action of grasping the top and bottom of the box at the front thereof, the cam surfaces 3 will engage and force the lid or cover down to its normal position and thereby insure that the lids or covers will be in their proper closed positions.

While the spaced shelf members D and E might serve for some purposes without a cover plate, I prefer to employ the cover plate C which is of relatively thin sheet metal having its front and rear edges bent downwardly to form substantially U-shaped beads or hooked portions 7 and 8, best indicated in Fig. 2 of the drawings, said open beads or hooked portions embracing the front edge of the front shelf member D and the rear edge of the rear shelf member E, respectively. It will be understood that the cover plate is of a length to extend between adjacent uprights only, and is fitted in place before the front shelf member is driven to its final position by the introduction of the key 4, which driving forward of the front shelf member stretches the cover plate into a taut rigid condition and maintains the cover plate in this condition so long as the key remains in place.

In Figs. 10 and 11 of the drawings, I have shown a shelf member H, which is composed of a single sheet of metal and has front and rear depending longitudinally extending ribs 9 and 10, of exactly the same cross-sectional shape as the ribs 1 shown in Fig. 2. Instead of having separate slots F and G, as in Fig. 2, there is a single slot J, the middle portion of which is straight and connects terminal portions F' and G' of the same configuration as the slots F and G in Fig. 3. The difference between Fig. 2 and Fig. 10 is that Fig. 2 shows two separate shelf members and a cover plate, whereas Fig. 10 shows a single shelf member which is the full width of the shelf and has two depending longitudinally-extending ribs.

Another embodiment of the shelf has been shown in Fig. 19 of the drawings, wherein the difference over the form shown in Fig. 2 of the drawings resides in the fact that the cover plate extends to the back wall 11 of the shelving and is provided with a down-turned flange 12, preferably corrugated and driven down between the back of the structure and the upstanding corrugated lip of an angle bracket 13 spot-welded or otherwise secured to the back 11. By this construction, the shelf may be made wide enough to extend clear back to the back plate 11, it of course being necessary to anchor the rear edge portion of the cover plate in order to hold the same when the cover plate is being stretched by the driving of the wedges 4 at the front of the structure.

By having the shelves terminate short of

the front and back of the structure, a considerable amount of metal may be saved, and there is less opportunity for the lodgment of dust and dirt at the back edge of the shelf.

At the end of a section of shelving, each shelf member of course extends into its slot or opening in the upright, but of course terminates flush with the outer face of the upright, and some means must be provided to hold or anchor the shelf member in place. One form of anchoring means has been shown in Figs. 4 and 5, consisting of a plate 11 provided upon its upper edge with a pair 15 of dove-tailed lugs or tenons bent at substantially right angles to the plate and occupying similarly shaped notches or recesses 13 in the adjacent end of the shelf member. The plate 11 of course lies on the outer face of the upright, and being interlocked with the shelf member, said plate effectually anchors the shelf member in place. This anchor plate, of course, moves endwise with the shelf member when the latter is 25 moved by the introduction of the wedges, so that the anchor plate does not interfere with the insertion of the keys.

In the form of shelf shown in Figs. 1 and 2, two anchor plates are employed at the end of the shelf, one for each shelf member, while a single anchor plate, of the proper length, is sufficient for the form of shelf shown in Fig. 10, such an anchor plate being shown at 14 in Fig. 16 of the drawings. 35 Two separate anchor plates are required for the form of shelf shown in Fig. 2, for the reason that the shelf members D and E are separately keyed in place, and consequently the anchor members must move with their 40 respective shelf members, while in Fig. 16 there is only one shelf member, and consequently a single anchor device is sufficient.

In Figs. 14 and 18, I have shown another form of anchor device for the end of a shelf member, wherein the end of the shelf member is provided with two pairs of ears 15 and 16, which are passed through the slot or opening in the adjacent upright and then bent in opposite directions against the outer 50 face of the upright.

Still another form of anchoring means has been shown in Figs. 8 and 9 of the drawings, wherein the shelf member is provided with a plurality of ears 17 lying in the plane 55 of the member and perforated to receive pins or keys 18 driven downwardly through the ears and on the outer face of the upright.

In Fig. 15, another embodiment of anchoring means has been shown. In this 60 figure, the shelf member is provided with a plurality of terminal depending ears 19, and the upright is provided with a notch or opening 20 of a size to receive the ear 19 therethrough in order that the ear 19 may 65 be located upon the outer face of the up-

right. When the keys 4 are driven into place and the shelf member is shifted forwardly, the ear or ears 19 will also be moved forwardly out of alinement with the adjacent opening, whereby the upright and the shelf member will be interlocked against separation.

When two shelving sections are brought end to end, as shown in Fig. 17 of the drawings, the anchor devices will register and space the end uprights, and therefore I propose to employ a filler strip 21 between the front portions of the uprights so as to close the space therebetween and present a neat and finished appearance. This filler strip 75 may be held in place in any suitable manner, such for instance as by screws, one of which has been shown at 22. The rear edge portions of the uprights may be connected in any suitable manner, as by a bolt 23. 85

Having thus described the invention, what I claim, is:—

1. Metallic shelving comprising spaced plate metal uprights having corresponding substantially horizontal slots extending transversely thereof, a plate metal shelf member extending through the slots and having an offset portion, and keys in the slots, each key engaging an edge of a slot and the offset portion of the shelf member 95 to wedge said shelf member edgewise in the slot.

2. Metallic shelving comprising spaced plate metal uprights having corresponding substantially horizontal slots extending 100 transversely thereof and provided with shouldered portions, a plate metal shelf member extending through the slots of the uprights and having an offset portion disposed in alinement with the shoulders of the slots, and keys in the slots, each key engaging the shoulder of the slot and the offset portion of the shelf member to wedge the latter edgewise in the slot.

3. Metal shelving comprising a series of 110 plate metal uprights having corresponding openings therein, each opening being provided with a shoulder, a shelf member extending through said openings, and keys driven between the shoulders of the openings 115 and the shelf member to wedge the latter in the openings.

4. Metal shelving comprising a series of plate metal uprights having corresponding openings therein, each opening having an 120 intermediate downward extension providing an upstanding shoulder, a shelf member extending through the openings and provided with a longitudinal depending rib, and keys driven between the respective shoulders and 125 the rib to wedge the shelf member in the openings.

5. Metal shelving comprising a series of plate metal uprights having corresponding 130 openings therein, a shelf member extending

through said openings and notched at one edge to receive the respective uprights, and keys driven into the openings and holding the shelf member in position.

5. Metal shelving comprising plate metal uprights having corresponding openings therein, each opening having an intermediate downward extension, the rear wall of the extension constituting an upright shoulder, the front wall of the extension being inclined upwardly at an obtuse angle, a shelf member extending through the openings and provided with a depending longitudinal rib of a shape corresponding to the shape of the 10 extension of the openings of less width than said extension, and keys driven in between the upright shoulders and the rib to wedge the shelf member in place.

6. Metal shelving comprising a series of 20 plate metal uprights having corresponding openings therein, a plate metal shelf member having a depending longitudinal rib struck therefrom, each opening having a downward extension, the shelf member extending 25 through the openings with its rib in the extension thereof, and keys driven into the extensions of the openings and engaging the rib to wedge the shelf member in place.

7. Metal shelving comprising a series of 30 plate metal uprights having corresponding openings therein, a shelf member extending through the openings and shiftable laterally therein, a cover plate anchored at one edge and engaged at its other edge with the 35 shelf member, and wedges driven into the

openings to shift the shelf member and tighten the cover plate.

9. Metal shelving comprising a series of plate metal uprights provided with front and rear corresponding openings, shelf members extending through the respective front and rear openings, wedge members driven into the openings and holding the shelf members in place, and a cover plate connected to the shelf members and covering the 40 tops thereof and held taut by the shelf members.

10. Metal shelving comprising an end upright provided with an opening, a shelf member having a portion lying in the opening, and an anchor plate upon the outer face of the upright, there being a dove-tailed mortise and tenon joint between the anchor plate and the adjacent end of the shelf member. 50

11. Metal shelving comprising an end upright having an opening therein, a shelf member having a portion lying in the opening and provided with a terminal dove-tailed notch, and an anchor plate on the exterior of the upright and provided with a dove-tailed tenon lying in the notch of the shelf. 60

In testimony whereof I affix my signature in presence of two witnesses.

CHARLES B. ULRICH.
